UNITED STATES PATENT OFFICE.

JOHN HIGHAM, OF LOS ANGELES, CALIFORNIA, ASSIGNOR TO COMBINATION FOLDING CAMP STOVE COMPANY, OF LOS ANGELES, CALIFORNIA, A CORPORATION OF CALIFORNIA.

CAMP-STOVE.

1,364,371.

Specification of Letters Patent. Patented Jan. 4, 1921.

Application filed September 27, 1919. Serial No. 326,906.

To all whom it may concern:

Be it known that I, JOHN HIGHAM, a citizen of the United States, residing at Los Angeles, in the county of Los Angeles and 5 State of California, have invented new and useful Improvements in Camp-Stoves, of which the following is a specification.

This invention relates to improvements in collapsible camp stoves, being more particularly an improvement upon my previous Patent No. 1,250,907 issued December 18, 1917.

The objects of this invention are to provide in a collapsible camp stove a grill accessible when desired and concealed by a solid plate at other times, to provide a rigidly formed top for the stove which supports the grill and solid portion of the top and also the said plate which is pivoted thereto, to provide a collapsible stove pipe hinged to the top of the stove and adapted to be collapsed and folded closely thereto and in the same plane therewith, all of the members of the stove being hinged or otherwise connected to one another so that they may be folded in close relation to the stove top and in substantially the same plane therewith and so arranged that when opened to operative position they may be rigidly locked and sustained in this position by means provided for that purpose.

The device is further provided with various other new and useful features of construction and arrangement as hereinafter more fully described and particularly pointed out in the claims, reference being had to the accompanying drawings in which:

Figure 1 is a perspective view of a collapsible camp stove embodying this invention shown set up in operative position with parts broken away.

Fig. 2 shows the stove partially collapsed with parts broken away.

Fig. 3 is a plan view of the stove with parts broken away.

Fig. 4 is a transverse sectional elevation on the line 4—4 of Fig. 3.

Fig. 5 is a fragmentary perspective view of one corner of the rear of the stove set up.

Fig. 6 is a perspective view of a lower end of the stove pipe set up and removed from the stove.

Fig. 7 is a sectional elevation through the

pivoted plate showing one of the supporting legs hinged thereto.

Fig. 8 is a transverse sectional elevation on the line 8—8 of Fig. 3 showing the plate over the grill.

Fig. 9 is a perspective view, illustrating 60 the stove as fitted with a foldable oven and showing the oven in its folded position.

Fig. 10 is a perspective view, showing the oven in its open position.

Like numbers refer to like parts in all 65 the figures.

1 represents the frame of the top of the stove to which the grill and solid portion of the top are attached and to which also the sides and rear end are hinged. The 70 front and bottom of the stove are left open, a bottom being formed by the ground upon which the stove rests when in use and the open front admits air to the fire.

The forward portion of the frame is cov- 75 ered by an open grill 2 and the back portion 3 is of solid sheet metal crimped around the frame 1. The sides 4 are attached at intervals by hinges 5 to the frame, these hinges as well as others used in this construction being attached preferably by electric welding although rivets may be used. The sides 4 have at their upper edges flanges 6 which extend a short distance over the top of the stove and at their bottom edges flanges 7 85 which rest on the ground and serve as feet.

The back 8 is attached by hinges 8^a to the frame 1 extending between the sides 4 and slightly forward of their rear ends and hooks 9 pivoted to the back 8 are adapted to extend through holes 10 in the said sides and serve the dual purpose of preventing the sides from spreading and also retain the back in its proper operative position. A spacing bar 11 is pivotally attached to the 90 foot flange 7 of one of the sides 4 near its forward end and the other end of the rod is upturned as at 12 and extends through a hole in the foot flange of the other side, thus retaining the lower edges of the sides at their 95 forward ends in proper operative position.

A triangular aperture 13 is provided in the solid portion 3 of the top of the stove and a three sided collapsible stove pipe is provided, the lower end of which is adapted 105 to fit into said triangular aperture. The stove pipe comprises the walls 14, 15 and 16, the wall 14 being connected to the stove top

3 by the hinge 17. The wall 16 is hinged to the wall 14 and the wall 15 is hinged to the wall 16, flanges 18 being provided on the walls to overlap the hinges and form substantially tight joints. The lower ends of the stove pipe walls extend below the said flanges 18 projecting through the aperture 13 and the lower ends of the said flanges engage the top of the stove and support the pipe in operative position.

10 A solid plate 19 is pivotally connected to the solid portion 3 of the top of the stove and adapted either to be positioned over and covering the grill 2 when it is desired 15 to have an entirely solid top to the stove or to be turned on its pivot to one side of the stove to expose the grill 2 for use, the outer end of the plate 19 being supported in this 20 position by hinged legs 20. The plate 19 is provided at its sides and forward end with down turned flanges 21 which both stiffen the plate and tend to form a substantially tight joint with the top of the stove. When 25 the plate 19 is turned to the side of the stove it serves as a support for cooking utensils and in this position a small fire may also be built under the plate and it may be used for cooking.

It will be seen that the stove when set up 30 in operative position has its various members rigidly connected and supported, that it provides a very convenient stove for camp cooking purposes embodying either a solid top stove or a grill and having an effective 35 stove pipe to carry away the smoke, and that when the plate 19 is extended to one side of the stove additional cooking surface is provided.

To collapse the stove the hooks 9 at the 40 back thereof are disengaged from the sides 4 and the spacing rod 11 disconnected and turned parallel with the side to which it is pivotally attached and the said sides are folded by virtue of their hinged connection 45 to the frame against the under side of said frame and parallel therewith. The stove pipe is collapsed by folding the side 15 against the side 16 and both of said sides against the side 14 and thus collapsed it is 50 folded by virtue of the hinge 17 against the upper surface of the stove top and the plate 19 is moved over the grill 2 covering the collapsed stove pipe and retaining it in place, the legs 20 being folded beneath the said 55 plate 19. The back 8 is folded upward on its hinges 8^a and arranged close to the upper surface of the stove top. Thus the whole stove is collapsed and occupies comparatively small space making it convenient for 60 transportation.

Special attention is called to the construction of the top of the stove in which the frame 1 extends integrally entirely around the said top, thereby forming a rigid means 65 of construction and providing convenient

means of attaching the folding members thereto. It is also pointed out that all parts of the stove are attached to one another so that there is no danger of any part becoming misplaced or lost. As a means for holding 70 the plate 19 against displacement in its folded position, a clamping hook 22 is mounted on the end cross member of the frame 1 and is adapted to be turned to engage the edge of the plate when the latter is in its folded 75 position, as shown in Fig. 2.

If desired, the stove may be fitted with a foldable oven 23 as illustrated in Figs. 9 and 10, and which oven is here shown as consisting of a pair of side panels 24 and 25 80 hinged transversely of the plate 19 and having top panels 26 and 27 hinged on the upper edges thereof and adapted to extend inwardly therefrom to form the oven top as shown in Fig. 10 and to be swung outwardly 85 against the outer faces of the side panels 24 and 25 in folding the oven upon the plate 19, as shown in Fig. 9. The oven is provided with an end panel 28 hinged on the plate 19 and having hooks 29 adapted to engage 90 openings 30 in the side panels for securing the side panels to the end panels and thereby hold the oven in its open position. A door 31 is hinged on the plate 19 for closing the open side of the oven; this door being 95 adapted to swing downwardly to give access to the interior of the oven and to be swung inwardly over the plate 19 when disposing the oven in its folded position.

If desired, the oven may be fitted with a 100 removable grid 32.

I claim:

1. A collapsible stove comprising a top part of which is solid and part a grill, the solid portion being provided with a smoke 105 outlet aperture, a plate pivoted to said solid portion and adapted to extend over and cover said grill or to be moved on its pivot to extend to one side of the stove, hinged legs on the movable end of said plate, a 110 collapsible stove pipe, one side of which is hinged to the solid portion of the top adjacent the aperture therein, and collapsible side walls hinged to said stove top substantially as described. 115

2. A collapsible stove comprising a rectangular frame, a grill covering part of said frame and attached thereto, a solid top covering the remainder of said frame and having a smoke outlet aperture there-through, a plate pivoted to said solid top and adapted to extend over and cover the grill or to extend to one side of the stove, hinged legs on the movable end of said plate, a collapsible stove pipe, one side of 120 which is hinged to said solid top adjacent the aperture therethrough, and side walls hinged to said frame. 125

3. A collapsible stove comprising a top, part of which is solid having a smoke out- 130

let aperture therethrough, and the remainder is a grill; a three sided collapsible stove pipe having one side hinged to the solid top adjacent said aperture, the said sides being hinged together and adapted to fold parallel with each other and also with the stove top, a plate hinged to said solid top and adapted to extend to one side of the stove or to extend over the grill and also 10 over said stove pipe when it is collapsed and folded parallel to said top, side walls hinged to said top and adapted to fold under the same, and an end wall hinged to said top and adapted to fold above the same.

15 4. In a folding camp stove, a stove body embodying a grill top portion, a plate pivoted to cover said top portion, and a foldable oven carried by said plate.

5. In a foldable camp stove, a stove body 20 having a top formed with a grill, a plate pivoted to cover said grill, a pair of panels hinged on said plate forming the side walls of an oven, an oven end panel hinged on said plate, means for connecting said end 25 panel to the side panels, and panels hinged to the upper edges of said side panels for forming an oven top.

6. In a folding camp stove, a rectangular 30 frame, a top plate secured to said frame and extending thereacross through a portion of the length thereof forming an open space bounded by the sides and one end of said

frame and the edge of said plate, a grill covering said open space affixed to said frame, side panels hinged to said frame extending throughout the side portions thereof and adapted to swing inwardly thereagainst, an end panel hinged to said frame, an auxiliary top plate hinged adjacent to one corner of said grill adapted to extend 40 to one side of the stove and to be disposed over the grill, and means for supporting the outer portion of said plate when positioned to the side of the stove.

7. In a folding camp stove, a rectangular 45 frame, a top plate secured to said frame and extending thereacross through a portion of the length thereof forming an open space bounded by the sides and one end of said frame and the edge of said plate, a grill 50 covering said open space affixed to said frame, side panels hinged to said frame extending throughout the side portions thereof and adapted to swing inwardly thereagainst, an end panel hinged to said frame, 55 an auxiliary top plate hinged adjacent to one corner of said grill adapted to extend to one side of the stove and to be disposed over the grill, means for supporting the outer portion of said plate when positioned 60 to the side of the stove, and a foldable stove pipe affixed to said top plate.

JOHN HIGHAM.
